UNITED STATES PATENT OFFICE

91,258

DESIGN FOR A CIGAR HOLDER

Henry Alberg, Millstadt, Ill.

Application October 14, 1933. Serial No. 49,486

Term of patent 7 years

To all whom it may concern:

Be it known that I, HENRY ALBERG, a citizen of the United States, residing at Millstadt, in the county of St. Clair and State of Illinois, have invented a new, original, and ornamental Design for Cigar Holders, of which the following is a specification, reference being had to the accompanying drawing, forming a part thereof, in which:

Fig. 1 is a front elevational view of a cigar holder, showing my new design.

Fig. 2 is a side elevational view.

Fig. 3 is a plan view.

I claim:

The ornamental design for a cigar holder, as shown.

In testimony whereof I affix my signature at 10 South La Salle Street, Chicago, Illinois.

HENRY ALBERG.
